UNITED STATES PATENT OFFICE

2,110,430

DISTRIBUTOR

Sven V. Swanson, Forest Park, Ill., assignor to Refrigeration Appliances, Inc., Chicago, Ill., a corporation of Illinois

Application March 5, 1937, Serial No. 129,244

12 Claims. (Cl. 62—126)

My invention relates to cooling units of refrigerating systems wherein liquid refrigerant is supplied to a duct or coil of the cooling unit to produce the cooling effect, and has reference more particularly to facilities for supplying equal amounts of refrigerant to each of several banks of coils.

In refrigerating systems of the type ordinarily used, a refrigerating medium is employed which, after compression, is introduced in liquid form through an expansion or control valve into the coils of a cooling unit wherein the refrigerant is evaporated and converted into gas, thereby lowering the temperature of the cooling unit or coils by the heat absorption which occurs in the conversion of the liquid into gas. In some cases, as for example in air conditioning equipment, wherein normal operation requires a high rate of heat transfer, the refrigerant is preferably introduced separately into a number of parallel banks of coils and in order to avoid the necessity of employing a separate expansion valve for each bank of coils it is desirable to provide a single expansion valve with a distributor which will properly proportion or equalize the supply of refrigerant to each bank of coils.

However, as some evaporation begins to take place as the refrigerant is discharged from the expansion or control valve, the refrigerant becomes a somewhat turbulent mixture of liquid and gas which does not distribute uniformly with ordinary distribution facilities and it is necessary to provide special distribution facilities which will properly proportion or equalize the supply or distribution of the refrigerant to the various banks of coils of the cooling unit.

It is therefore, an object of my invention to provide refrigerant distribution facilities for refrigerating systems which will insure uniform and equal distribution of the refrigerant from a single expansion valve to each of several banks of refrigerating coils.

Another object of my invention is to provide a refrigerant distributor wherein excess gas is removed from the refrigerant before distribution.

A further object of my invention is to provide a connection of the coil outlets with the return pipe to the compressor whereby uniform suction at all the outlets is assured, these and other objects being accomplished as hereinafter described, reference being had to the accompanying drawing, in which:

Fig. 1 is a vertical sectional view of a dis-

tributor constructed in accordance with my invention:

Fig. 2 is a cross sectional view taken on the line 2—2 of Fig. 1;

Fig. 3 is an end view of a coil unit with a number of superposed banks of refrigerating coils;

Fig. 4 is a view taken on the line 4—4 of Fig. 3 showing the take-off connections from the coil unit;

Fig. 5 is a view taken on the line 5—5 of Fig. 3 showing the expansion valve and the connections therefrom to the coil unit for supplying the refrigerant thereto; and

Fig. 6 is a sectional view of a header which may be employed in place of the take-off connections of Fig. 4 to insure uniform suction at all the tube outlets.

Referring to the drawing the reference numeral 10 indicates a multiple bank cooling unit 20 as a whole having four superposed banks 11 of coils, each bank of which comprises four laterally spaced parallel pipes 12, at the same elevation, connected in series by return bends 13 and supported by end plates 14 with fins or plates 15 on said pipes between the end plates 14 in accordance with the usual practice. Each bank of coils has an intake end 16 to which refrigerant is supplied and an outlet end 17 connected with a compressor (not shown) which withdraws the refrigerant gas from the coils and after compressing and condensing same into liquid form returns the liquid refrigerant through the pipe 18 to the expansion valve 19 from which it is supplied to the intake ends 16 of the coils.

To insure equalization of the suction effect of the compressor on each bank 11 of the coils, a manifold arrangement as shown in Fig. 4 may be employed with two manifold branches 20 leading respectively from the outlet ends 17 of the two upper banks 11 and from the outlet ends 17 of the two lower banks 11 and each branch 20 is centrally connected to the opposite ends respectively of the main branch 21 of the manifold which in turn is centrally connected to the pipe 22 which leads to the compressor so that the pipe distance of the outlet 17 of each bank of coils to the compressor is the same. Instead of the manifold arrangement of Fig. 4 a header 40 as shown in Fig. 6 may be provided, said header being hermetically closed at both ends in any convenient manner and provided with a central partition 41 extending from end to end thereof. At one side of the partition 41 the header has the tubes 12 connected thereto

- and at the other side of the partition the pipe 22 leads centrally from the header, and the said partition has the openings 42 therethrough which are equally spaced from the outlet 22 and the upper opening 42 is equally spaced between the two upper pipes 12 while the lower opening 42 is equally spaced between the two lower pipes 12 so that the path from all of the pipes 12 to the outlet 22 is of equal length.
- 10 Separate pipes 38, preferably of equal length, are connected to the respective inlet ends 16 of the banks of coils and supply refrigerant therefrom to the distributor 23 which in turn receives refrigerant through the pipe 24 from the expansion valve 18.
- This distributor which is shown in detail in Figs. 1 and 2 comprises a cup-like housing 25 with a cap or cover 26 secured thereto in a hermetically sealed manner as indicated at 27, and the pipe 24 from the expansion valve is hermetically secured centrally to the cap or cover 26 as shown, and communicates with the upper end of a conical recess 28 in the under side of said cap or cover. Under this conical recess 28 and centrally in the housing 25 is an upstanding annular flange 29 forming in effect an annular reservoir surrounding an inner cup from the bottom of which said inner cup the pipes 38 lead to their respective banks of coils, said pipes being hermetically secured to the bottom of the housing 25 at equal intervals around the bottom of the inner cup portion thereof formed by the flange 29. The bottom wall of said inner cup is centrally formed with a threaded recess 30 in which is engaged the lower threaded end of the stem 31 which is provided at the upper end with a conical spreader 32 of a somewhat flatter conical form than the conical recess 28 of the cap or cover 26 and which projects into said recess 30 to form between the recess 28 and spreader 32 a contracted annular passageway 33 by which the refrigerant entering the distributor is directed annularly downward into the annular reservoir between the flange 29 and the outer wall of the housing 25 from which reservoir the refrigerant overflows into the inner cup within the flange 29. It is to be noted that the discharge from the annular passageway 33 is against the surrounding wall of the housing 25 and this is advantageous as it minimizes disturbance and promotes quiescence of the liquid refrigerant in the annular reservoir so as to insure uniformity of outflow over the flange 29 into the central cup or basin from which the outlet pipes 38 lead.
- 45 Preferably the inner surface of the wall 29 is sloped at the bottom and the stem provided with a flared shoulder above the bottom of the inner cup as shown to direct the overflow from the annular reservoir to the outlets at the bottom of the cup.
- Obviously the distributor 23 should be set in a substantially level position so that the overflow from the annular reservoir into the inner cup is uniform around the flange 29 and when so set the supply of refrigerant to each of the pipes 38 is accordingly equal and uniform since the pipe outlets are uniformly arranged around the bottom of the inner cup into which the annular reservoir overflows.
- 50 Preferably a take-off is provided from the interior of the distributor 23 at the top of the chamber therein to remove excess gas from the refrigerant before distribution thereof to the pipes 38 and for this purpose the cap or cover 26 is provided with a bleeder passage 34 controlled

by a valve 35 and connected by the pipe 36 with the pipe 22 which leads from the cooling unit 16 to the compressor. Said pipe 22 also has secured thereto the thermostatic bulb 37 of the expansion valve whereby the supply of refrigerant furnished by the expansion valve to the cooling unit 16 is controlled.

While I have shown and described my invention in a preferred form, I am aware that various changes and modifications may be made without departing from the principles of my invention, the scope of which is to be determined by the appended claims.

I claim as my invention:

1. In a distributor of the class described, the combination of a housing with a chamber therein, said housing being formed to provide at the bottom of the chamber a cavity with a surrounding reservoir which overflows into said cavity, an inlet at the top of the housing and leading into said chamber thereof through an annular orifice which discharges into the aforesaid reservoir, and said housing having a plurality of outlets at the bottom leading from the bottom of the cavity into which the reservoir overflows.
2. In a distributor of the class described, the combination of a housing with a chamber therein, said housing being formed to provide at the bottom of the chamber a cavity with a surrounding reservoir which overflows into said cavity, an inlet at the top of the housing and leading into said chamber thereof, a spreader in the chamber between said inlet and the cavity and arranged to divert inflow from said inlet into the reservoir uniformly around the cavity, and said housing having a plurality of outlets at the bottom uniformly arranged around and leading from the bottom of the cavity into which the reservoir overflows.
3. In a distributor of the class described, the combination of a housing with a chamber therein, said housing being formed to provide at the bottom of the chamber a cavity with a surrounding reservoir which overflows into said cavity, and said housing being formed at the top with a conical recess opening into said chamber and concentrically disposed over and extending outwardly beyond the aforesaid cavity, an inlet at the top of the housing and leading into the top of the said conical recess at the apex thereof, a conical spreader projecting into said conical recess and forming therewith an annular passageway through which the inflow from said inlet is directed into the reservoir, and said housing having a plurality of outlets at the bottom uniformly arranged around the center of the cavity and leading from the bottom of said cavity.
4. In a distributor of the class described, the combination of a housing with a chamber therein and an inlet leading into the top thereof, said housing being formed to provide at the bottom of the chamber a cavity centrally disposed under said inlet and having a surrounding reservoir which overflows into said cavity, a stem projecting upwardly from the center of said cavity and having at its upper end a deflector in the path of the inflow through said inlet and by which such inflow is directed into the aforesaid reservoir, said housing having a plurality of outlets at the bottom uniformly arranged around said stem and leading from the bottom of the cavity into which the reservoir overflows.

5. In a refrigerating system, the combination of a cooling unit comprising a plurality of separate coils, each having a separate outlet connected

to a common discharge pipe, and means for separately supplying refrigerant to each coil from a common source, said means including a distributor comprising a housing with basins therein through which refrigerant supplied from the said common source flows consecutively, said basins being arranged to overflow one into another, and the last basin of the series having separate refrigerant conductors leading therefrom to the respective coils.

6. In a refrigerating system, the combination of a cooling unit comprising a plurality of separate coils each having a separate outlet connected to a common discharge pipe, and means for separately supplying refrigerant to each coil from a common source, said means including a distributor to which refrigerant is supplied from said source and having separate refrigerant conductors leading therefrom to the respective coils, said distributor comprising a housing with a chamber therein divided at the bottom into two basins one of which said basins has the aforesaid conductors leading therefrom and the other of which said basins receives refrigerant from said common source and overflows into the basin from which said conductors lead.

7. In a refrigerating system, the combination of a cooling unit comprising a plurality of coils, each having a separate inlet connected through a distributor with a common source of refrigerant supply, and each of said separate coils having a separate outlet communicating with a common discharge pipe, and connecting means interposed between the latter pipe and the coil outlets and comprising a header closed at the ends and having a central partition extending from end to end thereof and provided with two spaced openings therethrough, said header having the outlets of the coils connected therewith at one side of the partition and the common discharge pipe leading therefrom at the other side of the partition at an equal distance from the two spaced openings through the partition and each of said openings being equally distant from two coil outlets.

8. In a distributor of the class described, the combination of a housing having therein a chamber with a basin and with a reservoir that over-

flows into the basin, a plurality of outlets leading from said basin, and an inlet leading into the chamber and discharging into the reservoir against a side wall of the reservoir remote from the outlets.

5

9. A distributor of the class described, comprising a housing providing a chamber having a plurality of outlets equidistant from the surrounding wall of the chamber, and inlet means having an annular discharge orifice positioned to 10 discharge against and uniformly along said surrounding wall.

10. In a distributor of the class described, the combination of a housing having a chamber therein, a plurality of outlets leading from the bottom of the chamber, an intake leading into the chamber, and spreader means for directing and distributing the discharge from the intake in an annular stream surrounding the outlets at a substantially uniform distance from all the outlets.

11. The method of equalizing the distribution of a liquid refrigerant from an expansion valve to the separate coils of a cooling unit, said method comprising simultaneously discharging the refrigerant in a thin sheet from the expansion valve and so collecting the same as to form a quiet pool, directing overflow from said pool in a thin sheet over an edge portion thereof remote from the place where the refrigerant is discharged into 30 the pool, and conducting equal amounts of the overflow of refrigerant separately to the respective coils of the cooling unit.

12. In a distributor of the class described, the combination of a housing having a chamber 35 therein, a plurality of outlets leading from the bottom of the chamber, an intake in the top of the chamber and directed towards the bottom of the chamber, and conical spreader means within the chamber and located between the intake and the outlets and disposed for directing and distributing the discharge from the intake in an annular stream surrounding the outlets at a substantially uniform distance from all the outlets.
